UNITED STATES PATENT OFFICE.

FRANZ A. FULLER, OF NEWARK, NEW JERSEY.

RAZOR-BLADE.

1,135,008.

specification of Letters Patent. Patented Apr. 13, 1915.

Application filed April 28, 1913. Serial No. 764,065.

To all whom it may concern:

Be it known that I, FRANZ A. FULLER, a citizen of the United States, residing in the city of Newark, in the county of Essex and State of New Jersey, have invented certain new and useful Improvements in Razor-Blades, of which the following is a full, clear, and exact description, such as will enable others skilled in the art to which it pertains to make, construct, and use the same, reference being had to the accompanying drawings and to numerals of reference marked thereon, forming a part of this specification.

This invention relates to certain new and useful improvements in razor blades, provided with a longitudinal deflection serving to stiffen and strengthen the blade, as will be herein described.

The invention comprises the constructing of the blade from sheet steel with a concaved and offset portion, which will be found of importance in tempering, sharpening, honing and stropping the blade, and at the same time, presenting contacting surfaces for the fingers in handling the blade, thereby reducing the possibilities of cutting the latter in pressing the blade into or out of position, to a minimum.

In carrying the invention into practice, I provide also a means for supporting the blade.

Describing the invention in detail, reference is had to the accompanying drawings, forming a part of this specification, and wherein like numerals of reference indicate corresponding parts throughout the several views of the drawings, and in which—

Figure 1 represents a perspective view of a blade; and Fig. 2 represents a similar view of the means for supporting the blade, the means also being shown in operative position in dotted lines in Fig. 1.

In the accompanying drawings, 1 represents a razor blade made of very thin sheet steel, provided with a longitudinal cutting edge 2, and an upwardly projecting concaved portion 3 terminating into an offset 4, which serves to stiffen and strengthen the blade, thus rendering the same more rigid and durable in its nature.

In Fig. 1 of the drawings, I have shown my improved blade in combination with the means 7 illustrated in Fig. 2, for supporting the blade, said means being so formed and so arranged as to give to the razor blade 1

rigidity and stability, inasmuch as it is contemplated to use with the supporting means, preferably a blade of approximately the length of the so-called straight razor now in use, thereby presenting a structure in general appearance similar to said so-called straight razor. The supporting means 7 is also provided with a short concaved portion 8 extending throughout its entire length, the lower edge 9 of which is adapted to bear against the corresponding concaved portion of the razor blade 1 to support the same, said supporting means 7 being further provided with a channel-shaped portion 10 extending along its entire length, designed to receive the offset vertical upper portion 11 of the blade 1. The supporting means 7 may be of any size and form, and if desired, may have formed integral therewith, a handle or the like.

The construction of the blade is of such a nature as to lend itself to be readily manufactured by the use of ordinary punches and dies.

Experience has demonstrated that the organization above described is a highly efficient one, and while the device described is the preferred embodiment of my present invention, I do not care to restrict myself to the exact details of construction, combination and arrangement herein set forth, it being obvious that minor variations thereof not involving the exercise of invention may be made by any skilled mechanic, and such departures from what is herein described and claimed not involving invention, I consider within the scope and terms of my claim.

I claim:

The combination of a razor blade made of sheet metal provided with a substantially plane longitudinal portion, and having a single longitudinal cutting edge, said cutting edge lying approximately in an extension of said plane portion, the blade intermediate said portion and said edge having a portion uniformly inclined from said edge away from the central plane of said first mentioned portion and lying entirely on one side thereof, said plane having also an off-set portion connecting said inclined portion with said first mentioned portion, the lines of union between said offset portion and said other portion being straight lines approximately parallel to said cutting edge, and a reinforcing member for said blades

comprising two plane portions arranged in parallel relation and spaced apart to form a groove adapted to receive the first mentioned portion of said blade, said member being extended in the same general direction as said blade and into contact therewith along one face of said inclined portion.

This specification signed and witnessed this 26th day of April, 1913.

FRANZ A. FULLER.
